UNITED STATES PATENT OFFICE.

JOHN B. HADAWAY, OF SWAMPSOFT, MASSACHUSETTS, ASSIGNOR TO UNITED SHOE MACHINERY CORPORATION, OF PATERSON, NEW JERSEY, A CORPORATION OF NEW JERSEY.

SOLE-LEVELING MACHINE.

Application filed December 22, 1921, Serial No. 524,129. Renewed May 7, 1928.

The invention relates to machines for leveling the soles of boots and shoes and more particularly to that type known as "automatic" leveling machines.

5 In this class of leveling machines as compared with those of the "direct pressure" type, the shoe sole is acted upon by a comparatively small roll which, in some machines, is rapidly vibrated as it travels over the sole and repeatedly applies a rolling pressure to the sole at the point of operation as this point progresses along the sole, and thus shapes the sole to the bottom of the last by the application of a comparatively 10 light pressure repeatedly and progressively applied. In the machines as heretofore constructed variations in the lateral curvature at different parts of the shoe sole have been commonly secured by varying the relative 15 lateral inclination of the roll and shoe supporting jack during the travel of the roll along the sole. While these machines give satisfactory results on certain classes of work their use is not entirely satisfactory 20 for leveling shoes in which there should be a well defined line of demarcation between the shank and forepart as in shoes having high arch shanks. Their use also sometimes presents the disadvantage that the 25 pressure of the roll along one side of the sole tends to disturb or modify the shape given to the sole by the action of the roll along the other side.

The present invention provides an organization 30 which is free from these objectionable features of the prior automatic machines while retaining the features which are particularly adapted for successfully leveling many types of shoes when supported on the 35 usual wooden lasts, such as the comparatively small roll with its restricted sole engaging area and the light rolling pressure repeatedly applied as the roll progresses along the shoe sole. This is accomplished 40 in the construction shown by providing the periphery of the roll with a sole shaping form or matrix which extends approximately around the roll and also by providing novel means through which the roll is 45 positively rotated by the relative movements of the jack and roll lengthwise of the shoe sole. With this construction the matrix will 50 roll along the sole and during its travel each transverse element of the matrix will roll

back and forth lengthwise of the sole and 55 thus repeatedly impress its shape on the sole by a rolling pressure extending from side to side of the sole. The means for rotating the roll preferably consists of a spur gear on the roll shaft whose diameter is equal to the 60 mean diameter of the matrix and a segment or rack on the jack which is maintained in engagement with the gear during the travel of the roll over the shoe sole.

This engagement is maintained also while 65 the jack is in inoperative position and an untreated shoe is being inserted in the machine, so that the roll is held in proper position, both vertically and peripherally, to engage the shoe in the right manner, as the 70 leveling operation begins.

In accordance with a further feature, novel means is provided for adjusting the matrix roll in proper relation to the shoe, the construction shown comprising means 75 for adjusting the rack relatively to the jack and also a gage to assist in effecting the proper adjustment.

The invention will be readily understood from an inspection of the accompanying 80 drawings and the following description of the construction shown therein.

In the drawings Fig. 1 is a side elevation of a machine embodying the invention in its preferred form, Fig. 2 is a side elevation of 85 the shoe supporting jack and the leveling roll, and Fig. 3 is a front elevation of the same.

In the drawings the invention is shown embodied in a machine which is similar in 90 many respects to the machine shown and described in Letters Patent No. 1,239,664, granted Sept. 11, 1917, on an application of William C. Baxter.

In this machine the shoe to be leveled is 95 carried on a jack which is oscillated in an automatically determined cycle by power-operated mechanism similar to that of the machine shown in said patent. The jack comprises a toe post 2 mounted to turn on the fulcrum shaft 4 and a heel post 6 pivoted at 8 to the toe post and adjustable toward and from the toe post for different sizes of shoes by a screw threaded adjusting shaft 10. The shoe is leveled by a comparatively 100 small leveling roll 12 on the periphery of which is formed a matrix or form having a 105 shape and contour complemental to that

which is to be given to the sole. The roll is journaled in a vertically movable support 14 and may be vibrated lengthwise of the shoe sole by mechanism 16 such as shown in 5 the above patent. To maintain the form on the roll in time or register with the sole on the jack and to secure a rolling pressure as the roll traverses the sole, and as herein illustrated also during the vibration of the 10 roll, means is provided for positively rotating the roll by the relative movement between the roll and jack lengthwise of the shoe sole. As shown this means comprises a gear 18 secured to the roll shaft and en- 15 gaging a segmental rack 20 carried on the jack. The gear preferably has a pitch diameter which is equal to the mean diameter of the matrix on the periphery of the roll and the rack has a curvature approximating 20 the longitudinal curvature of the forepart of the shoe sole. The rack is carried by a frame 22 secured to guide rods 24 which pass through a bearing block 26 formed on the hub of the toe post piece of the jack. The 25 frame is forced upward by springs 28 to maintain the rack in engagement with the gear during the travel of the roll over the shoe sole. The rack is of such length that the gear also remains in engagement there- 30 with when, in accordance with a well known characteristic of machines of the type illus- trated the jack is in its outer inactive or inoperative position and is disconnected from the actuating mechanism, the rack 35 thus supporting the roll in a plane substan- tially tangential to the bottom of the toe of the shoe so that it will first engage the shoe without objectionable impact.

This construction insures that the rack 40 and gear shall maintain the matrix and shoe sole in registering relation so that each transverse element of the matrix acts on the complementary part of the shoe sole and also insures the application of a rolling pres- 45 sure as the jack is moved relatively to the roll and also during both the forward and backward vibratory movements of the roll.

In order that the sole may be properly shaped it is important that the ball line of 50 the matrix register with the ball line of the sole and the rack 20 is accordingly so mounted on the frame 22 that it may be adjusted lengthwise of the shoe sole. For this purpose the plate on which the rack is formed 55 is connected with the frame by a screw threaded adjusting shaft 32 and is secured in adjusted position by bolts 34 which pass through curved slots in the plate. This adjustment also permits the point on 60 the rack corresponding to the sole engaging position of the ball line of the matrix to be brought into line with the ball line of the sole in adjusting the jack for different sizes of shoes. To facilitate the adjustment of 65 the rack and through it the matrix roll so

that the ball line of the matrix will strike the ball line of the sole of the shoe supported on the jack a gage finger 36 is pivoted on the rack so that it may be swung into position to register with the ball line of the sole 70 or be swung back out of the path of the gear 18. The gage finger is located in line with the point on the rack which is engaged by the gear when the ball line of the matrix is in sole engaging position so that proper 75 adjustment of the rack and matrix for any shoe may be made by bringing the finger into register with the ball line of the sole. The finger may be held in either position by a leaf spring 38 engaging one of a series of 80 flat faces 40 formed on the hub of the finger.

While it is preferred to employ the construction shown and described in applying the invention to the machine of the patent referred to this construction is not essential 85 to the broader features of the invention and may be varied or modified as found desirable or best suited to the specific construction and mode of operation of the machine in which the invention is to be utilized. 90

What is claimed is:

1. A sole-leveling machine having, in combination, a shoe-supporting jack, a leveling roll having on its periphery a sole-shaping matrix which extends approximately around the roll, means for effecting relative movement of the roll and the jack lengthwise of the shoe, and a positive connection between the roll and the jack comprising a gear connected to the roll and a 95 rack mounted on the jack for positively rotating the roll by the relative movements of the roll and the jack lengthwise of the shoe to apply a rolling pressure to the sole. 100

2. A sole leveling machine having, in combination, a shoe supporting jack, a leveling roll having a sole shaping matrix on its periphery, means for effecting relative movement of the roll and the jack lengthwise of the shoe, means for vibrating the roll 110 during said relative movement, and means comprising a positive connection between the roll and the jack for positively rotating the roll by the relative movement of the roll and jack lengthwise of the shoe sole to 115 apply a rolling pressure to the sole. 120

3. A sole leveling machine having, in combination, a shoe supporting jack, a leveling roll having a sole shaping matrix on its periphery, means for effecting relative movement of the roll and the jack lengthwise of the shoe, and means for positively rotating the roll by the relative movement of the roll and jack adjustable to cause the ball line of the matrix to register with the ball line of a shoe upon the jack. 125

4. A sole leveling machine having, in combination, a shoe supporting jack, a leveling roll having a sole shaping matrix on its periphery, means for effecting relative 130

movement of the roll and the jack lengthwise of the shoe, means for positively rotating the roll by the relative movement of the roll and jack adjustable to cause the ball line of the matrix to register with the ball line of a shoe upon the jack, and a gage arranged to register with the ball line of the sole when the requisite adjustment is secured.

10 5. A sole leveling machine having, in combination, a shoe supporting jack, a leveling roll having a sole shaping matrix on its periphery, a gear connected to the roll, a rack movable heightwise of the shoe on the jack, and means for maintaining the rack in engagement with the gear.

6. A sole leveling machine having, in combination, a shoe supporting jack, a vibrating leveling roll having a sole shaping matrix on its periphery, a gear connected to the roll, and a spring-pressed upwardly or downwardly movable rack on the jack cooperating with the gear.

7. A sole leveling machine having, in combination, a shoe supporting jack, a leveling roll having a sole shaping matrix on its periphery, a gear connected to the roll, and a cooperating rack on the jack adjustable to bring the ball line of the matrix into register with the ball line of a shoe on the jack.

35 8. A sole leveling machine having, in combination, a shoe supporting jack, a leveling roll having a sole shaping matrix on its periphery, a gear connected to the roll, a cooperating rack on the jack adjustable to bring the ball line of the matrix into register with the ball line of a shoe on the jack, and a gage finger on the rack arranged to be thrown into register with the ball line of the shoe when the rack is adjusted to cause the ball line of the matrix to register with the ball line of the shoe.

45 9. A sole leveling machine having, in combination, a shoe supporting jack, a leveling roll having a sole shaping matrix on its periphery, a gear connected to the roll, a cooperating rack on the jack adjustable

lengthwise of the sole, and a gage on the rack arranged to cooperate with the shoe sole in indicating the adjustment of the rack and matrix. 50

10. A sole leveling machine having, in combination, a shoe supporting jack, a leveling roll having a sole shaping matrix on its periphery, a gear connected to the roll, and a cooperating rack on the jack having a curvature approximately equal to the longitudinal curvature of the forepart of the shoe sole. 55 40

11. A sole leveling machine having, in combination, a shoe supporting jack movable between inoperative and operative leveling positions, a leveling roll, power-operated means operative in an automatically determined cycle for relatively moving the roll and jack lengthwise of a shoe on the jack to level the shoe, and means for supporting the roll, while the jack is in inoperative position, in the proper position to pass substantially tangentially on to the bottom of the toe of the shoe in the power operation of the machine. 65 70

12. A sole leveling machine having, in combination, a shoe supporting jack, a leveling roll, means for relatively moving the roll and jack to level a shoe on the jack and permitting the jack to swing from under the roll when a shoe is to be removed or inserted, and means on the jack for supporting the roll in its normal idle position, in a plane tangential to the bottom of the toe of the shoe. 75 80

13. A sole leveling machine having, in combination, a shoe supporting jack, a leveling roll having a sole shaping matrix on its periphery, a gear connected to the roll, and a co-operating rack on the jack adjustable to bring the ball line of the matrix into register with the ball line of a shoe on the jack, the rack being constructed and arranged to support the gear while a shoe is being inserted in the machine. 85 90

In testimony whereof I have signed my name to this specification.

JOHN B. HADAWAY
